INVENTOR

Ira C. Douglass

BY
Nelson A. Hallauer
his ATTORNEY

UNITED STATES PATENT OFFICE.

IRA C. DOUGLASS, OF ROCHESTER, NEW YORK.

RADIATOR.

Application filed March 31, 1919. Serial No. 286,302.

To all whom it may concern:

Be it known that I, IRA C. DOUGLASS, a citizen of the United States, residing in Rochester, county of Monroe, and State of New York, have invented certain new and useful Improvements in Radiators; and I do declare to following to be a full, clear, and exact description of the same, taken in connection with the accompanying drawings, 10 forming a part of this specification.

My invention relates to radiators, especially to that class of radiators through which fluid such as steam or hot water is circulated for heating the interior of houses or other buildings. The principal object of my invention is to construct an improved radiator of this kind, cheaply of sheet metal and of such a form that its exterior surface is adapted to have a very thin coat of 20 enamel applied thereto.

More specifically the object of my invention is to construct a radiator of sheet metal in two parts which may be welded together along their edges and which is so constructed 25 as to secure perfect drainage, and which is substantially seamless.

Referring to the drawings;

Figure 1 is a side elevation of a radiator constructed according to my invention.

Figure 2 is an end elevation of the same, 30 Figure 3 is a horizontal section through the radiator shown in Fig. 1, a part being broken away, and

Figure 4 is a view similar to Fig. 3, showing a slightly modified form of construction.

Similar reference characters refer to the same parts in all the figures of the drawings.

40 A radiator constructed according to my invention comprises two parts 1 and 2, Figures 1, 2 and 3 stamped from sheet metal, preferably steel into the form clearly shown in Figure 3. The parts 1 and 2 are duplicates and the corrugations 3 and 4 are provided to increase the radiating surface and need not be of the exact form and size illustrated herein. The two parts 1 and 2 are placed together with their outer edges in

register and welded together along the edges electrically or by other suitable means, as indicated at 5. The ends of the radiator may be made with a plane surface as indicated in Figure 3 or formed with a corruga-

tion 6 as indicated in Figure 4 to increase 55 the radiating surface. The radiator is supported on legs 7 which are secured to the body portion by welding or other suitable means. The bottom of the radiator is constructed in substantially one plane to secure 60 perfect drainage and is adapted to be connected with a boiler or other suitable source of steam or hot water by means of the conducting pipes 8 and 9 which may be provided with the stop cocks 10 and 11 for 65 closing the pipes when the heat is not desired.

It will be noted that my improved radiator can be cheaply made by stamping the parts 1 and 2 and welding the seams 5 electrically. 70 A radiator thus constructed of sheet steel is sanitary since no sharp corners or deep crevices are formed and if desired a thin coating of enamel or glass, as indicated at 27, may be applied to its surface 75 to improve sanitary conditions and the general appearance of the radiator. It is impossible to enamel the surface of a radiator by the usual processes which is cast or compound of separate units. 80

If desired, I may employ means for reinforcing the material of my radiator as clearly indicated in Figs. 3 and 4 of the drawings. To this end, one or more rigid bars 28 of steel or other suitable material are secured to the inwardly curved parts of the walls of the radiator by welding on other suitable means. The braces or bars 28 are applied to the parts 1 and 2 before said parts are secured to each other, and when 90 the radiator is completed lie within the radiator and do not affect its appearance or sanitary qualities.

It will be noted that my radiator is constructed of sheet steel in which the seams 95 are electrically welded making it substantially seamless. Such a radiator presents a fine grained smooth surface to which enameling can be readily applied and which can be treated both internally and externally 100 with rust proofing processes commonly in use.

Having described my invention what I claim and desire to secure by Letters Patent is;

1. A radiator constructed of two sheet metal parts formed with corrugations to increase their surface areas and joined to

gether at their edges to form a closed chamber adapted to contain a fluid, and means secured to the corrugations of each of said parts within the chamber for reinforcing its walls.

2. A radiator constructed of two sheet metal parts formed with corrugations to increase their surface areas and joined together at their edges to form a closed chamber adapted to contain a fluid, and reinforcing

bars welded to said corrugations within the chamber.

3. A radiator constructed of two similar sheet metal parts formed with corrugations and smoothly joined together at their edges 15 to form a closed chamber adapted to contain a fluid, and reinforcing bars extending transversely of said corrugations and secured thereto within the chamber.

IRA C. DOUGLASS.
